Patented Aug. 3, 1920.

UNITED STATES PATENT OFFICE.

EDWARD G. HODGES, OF MARSHALLTOWN, IOWA.

SPEED-LIMITING DEVICE.

1,348,831.

Specification of Letters Patent.

Patented Aug. 3, 1920.

Application filed August 11, 1919. Serial No. 316,901.

To all whom it may concern:

Be it known that I, EDWARD G. HODGES, a citizen of the United States, and a resident of Marshalltown, in the county of 5 Marshall and State of Iowa, have invented a certain new and useful Speed-Limiting Device, of which the following is a specification.

My invention relates to speed limiting devices for internal combustion engines of the type in which there is no obstruction to the ordinary flow of fuel mixture to the engine cylinders.

The object of my invention is to provide 15 such a speed limiting device of very simple and inexpensive construction, having means operatively connected with a moving part of an engine or piece of machinery, and so arranged that when a certain predetermined 20 speed has been reached a valve will be operated for admitting a free flow or intake of air in addition to the normal air supply to the fuel mixture passage, for thereby thinning the fuel mixture to such an extent 25 as to immediately reduce the speed and hold it down to the desired limit.

A further object is to provide such a device so constructed and arranged as to permit a considerable variety of rates of speed 30 before the device becomes operative, and without affecting the ordinary fuel mixture supply.

Still a further object is to provide mechanism operatively connected with the means 35 hereinbefore described for automatically shutting off or reducing the fuel supply when the speed has reached a certain predetermined point.

With these and other objects in view my 40 invention consists in the construction, arrangement and combination of the various parts of the device, whereby the objects contemplated are attained as hereinafter more fully set forth, pointed out in my 45 claims and illustrated in the accompanying drawings, in which:

Figure 1 shows a side elevation of a speed limiting device, partly in section embodying my invention.

Fig. 2 shows a horizontal, sectional view 50 taken on the line 2-2 of Fig. 1; and

Fig. 3 shows a vertical, sectional view taken on the line 3-3 of Fig. 1.

In the accompanying drawings I have 55 shown a part of the upper fuel mixture passage or chamber of a carbureter indicated

by the reference character 10. Above the carbureter part 10 is a fuel mixture passage 11, designed to be suitably connected with the intake manifold of an internal combustion engine.

In the carbureter is a fuel nozzle 12. Communicating with the fuel mixture passage 11 is an air supply pipe 13. In the carbureter portion 10 is an ordinary manually controlled throttle of the butterfly type 14.

Suitably mounted is a governor consisting of a roatable shaft 15, having fixed thereon a collar 16. Slidably mounted on the shaft 16 is a sleeve 17 having at its opposite end 70 annular flanges 18 and 19.

Pivoted to the collar 16 are governor arms 20. Pivoted to the flange 18 of the sleeve 17 are governor arms 21. The respective arms 20 and 21 are connected with governor 75 balls 22. The shaft 15 is operatively connected by means of a flexible shaft 23 or other suitable mechanism with a moving part of an engine or other piece of machinery, whereby the governor device may 80 be operated according to the speed of such moving parts.

On the shaft 15 between the collar 16 and the flange 18 of the sleeve 17, is a coil spring 23a which yieldingly tends to hold 85 said parts apart, and to hold the balls 22 in close proximity to the shaft 15.

Suitably mounted in the pipe 13 is a butterfly valve 24 having a stem 25 extended through the wall of said pipe, and is provided on its outer arm with an arm 26.

Pivottally mounted on the stub 27 is a lever 28 having near one end an elongated slot 29, which slidably receives a pin 30 on the arm 26.

At the other end of the lever 28 is an upwardly extending arm 31, having at its upper end a right-angled extension 32 terminating in forked arms 33, which receive between them the sleeve 17. When the parts are in their normal position and are inoperative, the valve 24 is held in closed position by the spring 34 mounted on the stub 27 and fixed at one end. The other end of the spring 34 is connected with the lever 28, 100 and the said spring is so arranged as to tend to hold the lever 28 in position for holding the valve 24 closed when there is no tension on said spring 34.

In addition to the parts already described I preferably provide an extension 35 on the stem 25. On the extension 35 is a

beveled gear 36 in mesh with a beveled gear 37 mounted on a shaft 38. The shaft 38 extends through the wall of the carbureter part 10 and has fixed to it, on the inside of said carbureter part a swinging flap valve 39 arranged just above the fuel nozzle 12, and adapted in one of its positions to close the fuel nozzle 12.

It will be understood that the shaft 38 is located off center in the carbureter portion 10.

It will be seen that in the practical use of my improved speed governing device, an engine or motor vehicle on which my device is installed, may be operated through a considerable range of speed without being affected in any way by my device.

When, however, the moving parts, to which the shaft 23 is operatively connected, reach a certain predetermined speed, then the balls 22 will slide outwardly moving the sleeve 17 toward the left, as illustrated in Fig. 1. When the speed reaches a certain point, the flange 19 will engage the forked arms 33 for thereby actuating the extension 31, the arm 32, the lever 28, for moving the lever 28 and the arm 26 for opening the valve 24 and admitting the passage of air to the pipe 13 into the fuel mixture passage.

Where the fuel nozzle control valve is used, it will be seen that there is simultaneously a movement of the valve 38 toward closing position, for thereby shutting off the supply of fuel from the nozzle 12.

It will be understood that the parts of my device may be so constructed that the valve 39 will substantially shut off all flow of fuel from the nozzle 12 when said valve is closed, or will simply limit the flow of fuel from said nozzle 12.

It will also be understood that the length and proportion of the parts may be so varied as to regulate the action of the valve 24 for opening it to any desired degree when it is actuated through the operation of the governor.

Assuming that the engine has been running under proper conditions for effecting economy of fuel, and that the mixture used has been as thin or lean as properly should be used for maintaining the speed under the existing road conditions, then when the valve 24 is opened and an additional supply of air is admitted to the fuel mixture passage, the fuel mixture will be so thinned as to reduce or keep down the speed of the engine.

With some speed limiting devices there are extended into the fuel mixture passages, or into the intake manifold thick obstructions, such for instance, as a plug, or a valve whereby the carrying capacity of such fuel passages is reduced.

These fuel passages in a well built engine are constructed with a scientific regard for

the necessity of proper sized passages for supplying the engine cylinders with the necessary and proper volume of fuel mixture. Where such an obstruction is placed in the fuel passages, it will be obvious that the efficiency of the engine will be reduced, and in all probability there will be a loss of economy in the use of fuel, due to the fact that on account of the reduction in the size of the fuel mixture passage it is necessary for the operator to use a richer mixture than would be the case if such obstruction were not in the fuel mixture passage.

Where a governor is used in connection with a valve placed in some of the fuel mixture passages, it sometimes occurs that even though the obstruction in the fuel mixture is not very great when the valve is opened, yet when the engine reaches a speed somewhat below the predetermined maximum speed, the valve is partly closed, and during the time it is intended to operate the engine at almost the maximum speed, such operation will be interfered with and the efficiency of the engine reduced by the obstruction in the fuel mixture passage furnished by said valve.

My device is entirely free from the defects just mentioned. With my device the engine can be operated very nearly to the predetermined maximum speed without any interference whatever from my device, or can be operated right at the maximum speed with assurance of using a very lean mixture.

It will be understood that while the engine is operating right at the predetermined maximum speed, the air valve will be slightly opened and allow an additional amount of air into the fuel mixture. As soon as the speed goes any above the predetermined maximum speed, the valve will be opened further and will admit enough extra air to thin the mixture to such an extent that the speed will immediately drop back to the predetermined maximum speed.

When the speed of the engine is reduced, the valve 24 will be moved to closed position as soon as this is permitted by the governor, and immediately upon the closing of the valve 24 the engine can be operated under conditions favorable to fuel economy and engine efficiency without any obstructions in the fuel mixture passages.

The tension of the spring 23^a may be varied by adjusting the nuts 23^b for thereby determining the speed which will be required to operate the governor, and fixing the maximum speed for the engine.

The operation of my device is positive and certain.

I intend to cover by my claims any changes in the construction of my device from the particular construction shown in my drawings which may be reasonably in-

cluded within the scope of my invention and my claims.

I claim as my invention:

1. In a device of the class described; a fuel mixture passage; an air passage communicating therewith; a valve in said air passage; a governor designed to be connected with a moving part of an engine; and means for connecting said valve with said governor for actuating said valve after the governor has reached a certain speed of movement. 40
2. In a device of the class described; a fuel mixture passage; an air passage communicating therewith; a valve in said air passage; a governor designed to be connected with a moving part of an engine; means for connecting said valve with said governor for opening said valve after the 45 governor has reached a certain speed of movement; and means for normally holding said valve in a certain position of its movement. 50
3. In a device of the class described; a fuel mixture passage; an air intake passage communicating therewith; a valve in said second passage; means for normally holding said valve closed; a centrifugal governor including a slidably mounted sleeve; and means for connecting said valve with said sleeve, whereby said governor is permitted considerable movement without affecting said valve, and whereby when the 55 governor reaches a certain speed said valve reaches a certain speed said valve will be opened; a fuel nozzle in said passage; a throttle valve in said first passage between said fuel nozzle and said air intake passage; a valve for controlling said fuel nozzle; and means for operatively connecting said valve with said first means, whereby said last valve will be moved toward closed position when said first valve is moved toward open position. 60
4. In a device of the class described; a

fuel mixture passage; an air intake passage communicating therewith; a valve in said second passage; means for normally holding said valve closed; a centrifugal 40 governor including a slidably mounted sleeve; means for connecting said valve with said sleeve, whereby said governor is permitted considerable movement without affecting said valve, and whereby when the 45 governor reaches a certain speed, said valve will be opened; a fuel nozzle in said first passage; a valve for coaxing with said nozzle; and means for operatively connecting said valve with said first means. 50

5. In a device of the class described; a fuel mixture passage; an air intake passage communicating therewith; a valve in said second passage; means for normally holding said valve closed; a centrifugal governor including a slidably mounted sleeve; means for connecting said valve with said sleeve, whereby said governor is permitted considerable movement without affecting said valve, and whereby when the 55 governor reaches a certain speed said valve will be opened; a fuel nozzle in said passage; a throttle valve in said first passage between said fuel nozzle and said air intake passage; a valve for controlling said fuel nozzle; and means for operatively connecting said valve with said first means, whereby said last valve will be moved toward closed position when said first valve is moved toward open position. 60

Des Moines, Iowa, June 27, 1919.

EDWARD G. HODGES.
